(57) **CLAIM**

The ornamental design for the tester for electric vehicle service equipment, as shown and described.

DESCRIPTION

FIG. 1 is a generally frontal perspective view of a tester for electric vehicle service equipment showing my new design; FIG. 2 is a generally rear perspective view thereof; FIG. 3 is a front view thereof; FIG. 4 is a rear view thereof; FIG. 5 is a right side view thereof; FIG. 6 is a left side view thereof; FIG. 7 is a top plan view thereof; and, FIG. 8 is a bottom plan view thereof. The broken lines in the drawings illustrate unclaimed portions of the tester for electric vehicle service equipment and form no part of the claimed design.
